UNITED STATES PATENT OFFICE

118,977

DESIGN FOR A DECK OF PLAYING CARDS

Stanley Kermode, Christchurch, Hampshire,
England

Application September 5, 1939, Serial No. 87,056
In Great Britain September 20, 1938

Term of patent 14 years

To all whom it may concern:

Be it known that I, Stanley Kermode, a subject of the King of England, residing at Christchurch, in Hampshire, England, have invented a new, original, and ornamental Design for a Deck of Playing Cards, of which the following is a specification, reference being had to the accompanying drawings, forming part thereof.

Figures 1-55 are face views of the cards of the deck, showing my new design. The essential features of the front faces of the cards are a portion occupied by a domino representation, a

portion occupied by a letter of the alphabet or a symbol indicating that the card is a master card, and a portion occupied by the usual playing-card markings. The deck consists of fifty-five cards and has representations thereon for one set of hearts, clubs, diamonds and spades and three jokers. The backs of the cards are conventional.

I claim:

The ornamental design for a deck of playing cards, as shown and described.

STANLEY KERMODE.
